MANIFOLDING BOOK

Original Filed June 26, 1924

UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, PROVINCE OF ONTARIO, CANADA, A CORPORATION OF ONTARIO, CANADA

MANIFOLDING BOOK

Application filed June 26, 1924, Serial No. 722,436. Renewed March 6, 1930.

This invention relates to manifolding devices and with respect to its more specific features, to manifolding books adapted for use as salesbooks.

5 One of the objects of the invention is the provision of a manifolding book of the record storage type, adapted, at one writing, to produce three copies, each of which is of great legibility, and in which two of the 10 copies are of a character to increase the difficulty of making changes of the inscription without detection.

Another object of the invention is the provision of a practical form of triplicating book in which the original and triplicate copies may either record the inscription on 15 both faces, or on only one face, and in which the same transfer sheet and the same triplicate leaf may nevertheless be utilized to obtain either of these results.

Another object of the invention is the provision of an efficient manifolding book, which, while permitting use to obtain the three copies above mentioned, may nevertheless also be utilized to produce either four or 20 five copies at one writing without altering the mechanical construction of the book.

Other objects of the invention are to provide a triplicating book of the character described whereby chances of error in setting the book for inscription are lessened; adapted largely to avoid impairment of certain fragile leaves of the book, and adapted to facilitate manipulation of the book and auditing of the resultant records.

Other objects of the invention will in part be obvious and will in part appear herein-after.

40 The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in which:

Figure 1 illustrates a diagrammatic perspective view, with parts broken away, of a manifolding book embodying the invention, and

Fig. 2 illustrates a detail of one of the sheets.

The numerals 1 and 2 indicate a pair of backing members hinged to each other at 3. The backing members should preferably be of rigid material such as would be provided by heavy cardboard and the hinge may be composed of a flexible fabric strip connecting the members 1 and 2 as indicated. To each of the backing members a record pad is secured. The pad secured to the backing member 2 is indicated generally by the numeral 4, and that secured to the backing member 1 is similarly indicated by the numeral 5.

The pad 4 is made up of a plurality of superposed sheets, each of which is folded on itself along a line 6 to provide an original leaf 7 and a duplicate leaf 8 in superposed relation to each other. Each of the duplicate leaves 8 has an extended portion 9, and the extended portions of these leaves are bound together by the staples 10, which staples also are utilized to fasten the pad 4 to the backing member 2. The sheets of the pad 4 may be weakened, as by being perforated along the line 6, in order to permit them readily to be torn apart. Also each duplicate leaf 8 will preferably have a line of perforation 11 adjacent the stub of the pad to permit them to be torn from the stub with facility and accuracy.

The sheets of the pad 5 are adapted to be set in manifolding relation between the original leaves 7 and the duplicate leaves 8 to provide a third, or triplicate copy. In some instances the leaves 5 may be of opaque manifolding paper, as are the original and duplicate leaves 7 and 8, but in the embodiment illustrated, the leaves of the pad 5 are of transparent material, as tissue paper, which takes up less volume than opaque paper and which permits a record on one face to be visible from the opposite face. As illustrated, the leaves, or sheets, 5 are secured to the backing member 1 at the end

of the latter opposite the hinge 3. It will be observed that the lower backing member 1 is longer than the backing member 2, and that the leaves of the pad 5 are secured to the backing member 1 at a distance from the adjacent end of the backing member 2, the leaves of the pad 5 being secured to the backing member by the staples 12, the stub end of the pad 5, in the present embodiment, being parallel to the stub end of the pad 4, and the leaves of pad 5 being thereby adapted to be thrown back into the position illustrated in the drawing, so that individual leaves may be drawn across the stub of the pad 4 and interposed between the topmost of the sets of original and duplicate leaves 7 and 8.

It will be further noted that a relative separating movement between the backing members may be accomplished, for instance, by turning the backing member 2 on the hinge 3. This will provide a pocket between the backing members and it will be noted that the triplicate leaves of pad 5, while still secured to the backing member 1, may be received in such pocket and are adapted to lie flat therein when the backing member 2 is turned in the opposite direction so as to lie on the leaves in the pocket.

Suitable transfer material is secured to the book for the purpose of transferring inscriptions from the original copy, or leaf, 7 to any operatively underlying copies. In the present embodiment, a transfer carrier sheet is secured at one of its ends to the stub of the pad 4. As illustrated, this carrier sheet comprises two superposed leaves 13 and 14 connected together at one side, or end, as indicated at 15, the opposite end of the leaf 14 being bound on the top of the stub of the pad 4 by the staples 10. Thus the carrier leaves 13 and 14 may be interposed between the topmost set of original and duplicate leaves 7 and 8 of the pad 4 and may also receive between them one or more of the triplicate leaves of the pad 5, or a triplicate leaf of pad 5 may be disposed between the original leaf 7 and the upper carrier leaf 13, if desired. In the present embodiment the carrier leaves 13 and 14 are integral parts of the carrier sheet, which is folded at 15.

In the embodiment illustrated, each of the carrier leaves 13 and 14 has transfer material, as carbon, on both faces, such material covering an area of a sufficient extent to provide for transferring to underlying record leaves inscriptions made on the outer face of the original leaf 7. Also one carbon of each of the transfer leaves, as for instance indicated at 16 and 17, may be notched to permit the thumb and finger to have ready access to an underlying original leaf 7 for the purpose of manipulating such latter leaf in the operation of setting the

book. At the end of the transfer sheet 13, remote from the connection of this sheet with the pad, it is preferred to omit the transfer material for a small area on each face to provide a clean space, or handle, 18 projecting beyond the margin of the transfer material at this end.

Whatever be the number of copies it is desired to make at one writing, it is preferred that the leaves of the two pads shall be properly numbered so as to identify with each other all the leaves of a single manifolding set, and so as to distinguish the leaves of one set from those of another set. In the embodiment illustrated, when three copies are desired, the sheets of the pad 4 are numbered in series, as for instance from 1 to 50, beginning at the topmost sheet of the pad 4. The topmost sheet will therefore be numbered 1, and this number will be visible on the upper face of the original leaf 7, and will be found on the upper face of the duplicate face 8. Similarly the next underlying original and duplicate leaves 7 and 8 will be provided with a number 2, etc. As the book appears in the drawing the two sheets numbered 1 and 2 of pad 4 have been torn off, and the corresponding triplicates are shown in the pocket between the backing members 1 and 2. The leaves of the triplicate pad 5 will be similarly numbered from 1 to 50, the number 1 being applied to the lower, or inner triplicate leaf, which is bound in the stub of the tissue pad, the numbers reading upwardly in this pad and therefore being in reverse order to the reading of the numbers in the pad 4. The numbers of the pad 5 will be applied to the upper faces of the leaves and in such position that when one of these leaves is in manifolding relation to those of the pad 4, as illustrated in the drawing, the number on the triplicate leaf will be visible along with the number on the original leaf 7, when the book is set for inscription. In this way, the operator can readily observe the numbers on the original and triplicate leaves, verifying that these leaves belong to the same set, and if they do not so belong, may make any desired change. The numbers on the original leaves are indicated at 19, those on the duplicate leaves at 20 and those on the triplicate leaves at 21.

In addition to the numbering of the triplicate leaves as at 21, each triplicate leaf is also provided with an indicator 22 consisting, in the present embodiment, of the depiction of a pointing hand, on the same face of the leaf as is the number 21.

The indicator calls attention to the number of the triplicate leaf by pointing to it, and is especially useful for those having no great familiarity with the operation of manifolding books of this type. But when they set the book, the hand immediately di-

rects their attention to the number, whereupon they compare it with the number on the original leaf and proceed as noted. Furthermore all operators become accustomed to finding the indicator in correct position when the book is set for inscription. If by some possibility, the triplicate leaf should not have been turned from the pad 5 and laid in manifolding position, 10 the absence of the indicator in its customary clearly visible position will immediately be noted, and, if this is not enough, the operator observes that the only hand 22, he can see, is but dimly visible through the turned 15 back tissue leaf, and this abnormality further calls the operator's attention to the inaccurate setting of the book.

The numeral 23 indicates an outer flexible cover leaf for the pad of triplicate leaves. 20 In the present embodiment, this cover is of thin material, such as thin manila paper, and exceeds the pad 5 in length, and is extended so as to provide a part, or flap, 24 which may be folded around the free ends 25 of the leaves of the pad 5 so as to provide a pocket for the reception of such ends and protect them, without interfering with the free manipulation of the triplicate leaves in the operation of the book. The numeral 30 25 indicates another flexible cover leaf of thin manila paper, having a fold or flap 26 adapted to enclose the free ends of those leaves of the pad 5 which may be stored between the backing members 1 and 2. Thus 35 the leaves of the triplicate pad 5 are enclosed between flexible inner and outer cover leaves 23 and 25 which have thin flaps adapted to fold around the free ends of one or more leaves.

40 For making three copies, including an original and two carbons, a leaf of the triplicate pad 5 may be set, as illustrated in Fig. 1, between the two doublefaced transfer leaves 13 and 14 and between the original 45 leaf 7 and the duplicate leaf 8. With this setting, inscription on the original leaf 7 will be duplicated on the back of the original; on the upper and lower faces of the triplicate leaf and on the duplicate leaf 8. 50 Thus both the original and the triplicate leaves will have the inscription on each face. This will make it difficult to make erasures on either without detection and, when either leaf is a tissue leaf, the copied inscription 55 will be of increased visibility and easily read. When the book is set for inscription the corresponding set numbers, indicated at 19, of the original and triplicate leaves will be visible together for comparison, and the 60 indicator 22 will be in normal erect position. Having made the inscription, the backing member 2 may be lifted carrying the pad 4 therewith, the backing member turning at the hinge 3 so as to form the pocket or opening 65 between the backing members to receive

the inscribed triplicate leaf which will automatically drop into place and be held between the backing members on their return to closed relation. Thereupon another setting of the book may be effected in the same 70 manner as will be understood.

It will be seen, however, that two, instead of one, of the adjacent triplicate leaves may be placed between the double faced carbon leaves 13 and 14, whereupon four copies may 75 be obtained at one writing, one of the leaves of pad 5 receiving the copy on its upper face and the other on its lower face. With such arrangement it will be well to give the two triplicate leaves the same set number as 80 that on the original leaf, as will be understood.

Or the two leaves of pad 5 might be set, one between the original 7 and the upper carbon leaf 13 and the other between the 85 two carbon leaves 13 and 14, in order to obtain four copies. Or if only three copies are desired one triplicate leaf might be set between the original leaf 7 and the upper carbon leaf 13. In either of these two instances 90 the original leaf would not receive the inscription on its back and would be clean, being prevented from receiving the inscription by the triplicate leaf intervening between the carbon surface of the transfer leaf 95 13 and the leaf 7.

Or two triplicate leaves might be set between the carbon leaves 13 and 14, and a third triplicate leaf set between the original 100 7 and the carbon leaf 13, thus providing for five copies at one writing. In this setting the back of the original remains clean.

In making three copies with the book set as in Fig. 1, using only one triplicate leaf, the transfer material on the upper face of the leaf 14 might be omitted, in which event there would be obtained a direct reading tissue leaf and an original leaf 7, the latter having the inscription on each of its opposite faces.

110 In case it should be desired to remove some of the triplicate leaves instead of storing them between the backing members, the leaves may be provided with lines of perforations 30 to facilitate their accurate tearing from the stub. This is particularly desirable when two or more leaves of the triplicate pad 5 are employed for the same inscription. When the leaves of the pad 5 are thrown back as illustrated in Fig. 1, the 115 ends of the leaves are enclosed between the manila cover sheet 23 and the extension 24 thereof, and are thus protected although they may be readily manipulated and set as desired. The triplicate leaves may also be provided adjacent their free ends with a number 31 corresponding to the set number 21 of such leaf. When auditing the book this number, being at the end of the leaves, 120 enables the auditor to rapidly turn the leaves 125 130

and at the same time observe the numbers thereof. It will be noted that such used leaves of the pad 5 as are stored between the backing members are enclosed at their ends between the manila cover 25 and the flap 26. This flap is intended to be brought over the ends of the used leaves which have been audited, so as to separate these leaves from the unaudited leaves of the pad 5 which lie in the pocket. Thus the flap 26 acts as a book mark to tell the auditor where to resume auditing operation.

In Fig. 1, the pad 4 is illustrated as of considerable thickness and is provided with an additional folded transfer sheet 32 intermediate the depth of the pad which is similar in its construction and operation to that of the transfer sheet comprised by the leaves 13 and 14. The sheet 32, however, takes the place of the leaves 13 and 14 when the original and duplicate leaves lying thereabove have been exhausted.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A manifolding book comprising, in combination, two record pads, each of the sheets of one being folded on itself to provide an original leaf and a duplicate leaf in superposed relation to each other, the sheets of the other pad providing triplicate leaves adapted to be set in manifolding relation with said original and duplicate leaves, a pair of hinged backing members, one of said pads being secured to one backing member and the other to the other backing member so that relative separating movement between said members is adapted to provide a pocket therebetween for reception of said triplicate leaves while secured to their said backing member, a transfer carrier sheet secured to the book and comprising two superposed leaves connected together at one side adapted to be interposed between the topmost of the original and duplicate leaves of the relevant pad, said carrier leaves adapted to receive said triplicate leaves therebetween, and said triplicate leaves adapted to be disposed between said original leaf and the upper of said carrier leaves,

each of said carrier leaves having transfer material on both sides, the upper of said transfer leaves having a clean handle projecting beyond the margin of transfer material at the end of the transfer sheet remote from its connection to the book.

2. A manifolding book comprising, in combination, two record pads, each of the sheets of one being folded on itself to provide an original leaf and a duplicate leaf in superposed relation to each other, the sheets of the other pad providing triplicate leaves adapted to be set in manifolding relation with said original and duplicate leaves, a pair of hinged backing members, one of said pads being secured to one backing member and the other to the other backing member so that relative separating movement between said members is adapted to provide a pocket therebetween for reception of said triplicate leaves while secured to their said backing member, a transfer carrier sheet secured to the book and comprising two superposed leaves connected together at one side adapted to be interposed between the topmost of the original and duplicate leaves of the relevant pad, said carrier leaves adapted to receive said triplicate leaves therebetween, and said triplicate leaves adapted to be disposed between said original leaf and the upper of said carrier leaves, and an outer cover for the pad of triplicate leaves having a pocket for receiving the free ends of said triplicate leaves.

In testimony whereof I affix my signature.

EDWARD KIRBY BOTTLE.
